CLAIM

The ornamental design for an electrical socket, as shown and described.

DESCRIPTION

FIG. 1 is a back elevation view of an electrical socket showing our new design;

FIG. 2 is a top plan view thereof;

FIG. 3 is a front elevation view thereof;

FIG. 4 is a bottom plan view thereof;

FIG. 5 is a left side elevation view thereof;

FIG. 6 is a right side elevation view thereof;

FIG. 7 is a top, front, right-side perspective view thereof;

FIG. 8 is a bottom, back, left-side perspective view thereof; and,

FIG. 9 is a top, back, left-side perspective view thereof. The broken lines in the figures are for the purpose of illustrating portions of the electrical socket that form no part of the claimed design.
